Henry Pierce Sharon Conn.

Letters Patent

8th

The Schedule annexed to the Letters Patent and making part of the same containing a description in the words of the said Henry Pierce himself of his improvement in the Manufacture of Bridle Bits

To all to whom these presents shall come Be it known that I Henry Pierce of Sharon in the County of Litchfield and State of Connecticut have invented a new and useful improvement in Manufacturing of Bridle bits and that the following is a full and exact description of the construction and Manufacture of said Bridle bit as invented by me viz. said Bridle bit is made of iron of any suitable size with a mortised joint in the Centre, the iron to be cast into four pieces, two of which are of equal length forming the Cheeks or Side pieces the other two of equal length are twisted together and rounded at each end on to the Cheek or Side pieces and joining the Centre or mouth piece of the bit of a joint is made in the middle of the bit then each mouth piece is rounded at each end on to the same cheek or side pieces being twisted and run to the Centre of the mouth piece, and there is no joint in the Centre of the mouth piece. But if there is no joint in the bit then the wires forming the mouth piece of the bit are twisted together and fastened or bound at each end with the Cheeks or side pieces. The Cheeks or side pieces are formed by a piece of iron with circles or loops formed on each end and on which the ends of the mouth pieces are rounded and also forming a loop or nearly a circle in the Centre for the bridle to run. To form a Crib bit the side or cheek pieces are bound in the same manner only enough longer to form the loops at each end and the fast double under the meetings of the mouth pieces
